UNITED STATES PATENT OFFICE.

WALTER C. STONE, OF WEBSTER GROVES, MISSOURI.

REFRIGERATOR CAR.

Application filed April 4, 1927. Serial No. 180,744.

This invention relates to improvements in refrigerator cars.

In the operation of refrigerator cars at the present time, it is customary to locate 5 the drain pipe for the ice box in the floor at a point inwardly of the side wall of the car and also inwardly of the usual under-frame side sill and at the end of the car over the truck. With this arrangement, the 10 melted ice continuously drips onto the truck causing an unsightly slimy condition and unnecessary deterioration of the truck parts due to increased corrosion.

One object of my invention is to provide 15 simple and inexpensive means to overcome the disadvantages above indicated in present types of refrigerator cars and to assure the discharge of the water from the ice box to a point outside and clear of the 20 trucks.

A more specific object of my invention is to provide an arrangement of the general 25 character above indicated, which may be used not only on new equipment, but also readily applied as an attachment to refrigerator cars now in service without necessitating any change in the car construction of the latter, nor any change in the standard 30 drain appliances employed.

Other objects of the invention will more 35 clearly appear from the description and claims hereinafter following.

In the drawing forming a part of this 40 specification, Figure 1 is a broken, vertical, 35 sectional view, taken transversely of a refrigerator car showing the drain pipe arrangement with my improvements in connection therewith. In dotted lines is indicated the upper portion of one of the car 45 wheels in order to bring out the relation of the parts. And Figure 2 is a part plan view, 50 part horizontal, sectional view corresponding to the broken line 2—2 of Figure 1.

In said drawing, 10 indicates a channel 55 side sill of a refrigerator car underframe, 11 the usual flooring comprised of multiple layers of planks and 12, the insulated side wall structure, the details of which it is unnecessary to enter into. As customary in 60 refrigerator cars, the drain pipe is located as clearly illustrated in Figure 1, that is, inwardly of the side wall of the car and inwardly of the side sill and at a point over 65 the car truck. A common form of drain appliance is indicated in the drawing which 70 consists of a bowl 13 counter-sunk into a

suitable opening 14 cut out from the flooring, the bowl having an annular upper flange 15, seated flush in the top planking. The bowl 13 has a short pipe section 16 at 60 its bottom end, inclined at a slight angle to the vertical and toward the outer side of the car, said pipe section being received in a suitable smaller opening 17 in the lower planking of the floor. As customary, a drain pipe 18 is inserted through the pipe section 65 16 of the bowl, the pipe 18 extending at a corresponding angle and having the upper part or inlet end thereof raised an appreciable distance above the bottom of the 70 bowl, and the lower or discharge end thereof extended downwardly several inches below the floor level. A pivotally mounted cover plate 19 is attached to the bowl 13 and adapted to seat over the inlet end of the 75 drain pipe 18 while permitting access to the latter from the interior of the car when the cover 19 is lifted. The parts so far described are or may be of any well known or desired construction. As will be understood 80 by those skilled in the art, the water will collect in the bowl 13 until the lever rises to the lowermost edge of the inlet end of the pipe 18 and will then drip off of the lower edge of the outlet end. With such an 85 arrangement, it is obvious that the drippings will fall down onto the truck parts immediately therebelow and keep the latter constantly wet, the drippings spattering as the car is in motion. This causes an un- 90 sightly condition of the truck and obviously 95 promotes excessive corrosion.

In carrying out my invention, I provide what may be termed an attachment in the 100 form of a spout designated generally by the reference character A. This attachment is preferably in the form of a casting of approximately U-cross-section. At its upper end, the width of the spout is greater, as indicated at 20 and narrower at its lower end 105 as indicated at 21. At its upper end, the spout has the sides united by a rounded end wall, the upper end of the spout being such that the lower end of the drain pipe 18 may be projected thereinto in the manner indicated in Figure 1. At its lower end, the spout A is provided with a flange lip 22, the spout being extended through an opening 23, cut in the side sill 10 so that the water 110 as it drips off of the spout will be delivered at a point outside of the side sill and entirely clear of the truck. In the specific

form shown, the spout is provided with integrally formed flanges 24 and 25, the former being adapted to be riveted to the web of the channel side sill and the latter bearing upon the lower flange of the side sill. A strengthening rib 26 may be used uniting the main portion of the spout with the attaching flange sections.

As will be understood by those skilled in the art, different underframe constructions may necessitate somewhat different means of attaching the spout to the underframe structure.

Near the upper wide end of the spout, the lower wall of the latter is provided with an integral upwardly extending short pipe section 27 which, when the spout attachment is in position, will be inclined parallel to and approximately concentric with the axis of the drain pipe 18. The pipe section or opening 27 is provided in order to permit the insertion of a stick or tool for cleaning out the pipe 18, should that become necessary.

With the arrangement shown, and described, it is obvious that the water will drip off of the edges of the pipe 18 into the spout A and will flow down the latter as hereinbefore described. Due to the pipe section 27, rising above the bottom wall of the spout, none of the water will drip through said pipe section 27, it being understood that there is never any steady flow of water through the drain pipe 18, but rapid dripping.

The arrangement shown and described obviously may be manufactured at comparatively small expense and may be applied either to new equipment or to old equipment without modification of the car structure or of the usual drain pipe appliances.

I have herein shown and described what I now consider the preferred manner of carrying out my invention, but the same is merely illustrative, and I contemplate all changes and modifications that come within the scope of the claims appended hereto.

I claim:

1. In a refrigerator car having an ice box and a drain pipe therefrom located adjacent the side of the car but inwardly thereof: an extension drain pipe extending from beneath the discharge end of the drain pipe to a point outside the line of the car trucks whereby to discharge from the ice box to a point clear of the trucks, said extension drain being supported on said car independently of said drain pipe.

2. In a refrigerator car, having a drain pipe located with the discharge end thereof inwardly of the side sill of the car underframe: an extension drain spout extending from a point beneath the discharge end of said drain pipe to a point outside of the side

sill; and means for attaching said spout to the side sill.

3. In a refrigerator car having a drain pipe with the discharge end thereof disposed inwardly of the side sill of the car: an extension drain spout extending from a point beneath the discharge end of the drain pipe to a point outside of the side sill, said side sill having an opening therein through which the lower end of said spout is extended.

4. In a refrigerator car having a drain pipe inclined at an angle to the vertical and with the discharge end thereof located inwardly of the side wall of the car: an extension drain spout disposed beneath the lower end of said drain pipe and arranged to catch the drippings therefrom, said spout having an opening therein alined with the drain pipe to thereby permit access through the spout to said pipe, said opening being disposed out of line with the normal discharge from the drain pipe, and said drain spout having a flange disposed about said opening to prevent passage of said discharge through said opening.

5. As an article of manufacture, a drain spout adapted for attachment to a refrigerator car beneath the floor thereof, said drain spout having a receiving end within which is adapted to be positioned the discharge end of a drain pipe; and means on said spout by which the same may be attached to the car structure.

6. A drain spout attachment for a refrigerator car, having a drain pipe with the discharge end thereof extending below the floor level and located inwardly of the side wall of the car, said spout having an open upper end within which the discharge end of the drain pipe is adapted to be received and a lower discharge end extended to a point outwardly of the car truck; and means for attaching said spout to the car structure.

7. A drain spout attachment for a refrigerator car having a drain pipe with the discharge end thereof extending below the floor level and located inwardly of the side wall of the car, said spout having an open upper end within which the discharge end of the drain pipe is adapted to be received and a lower discharge end extended to a point outwardly of the car truck; and means for attaching said spout to the car structure, said spout having an opening in the bottom wall thereof surrounded by an up-standing flange, said opening being alined with the drain pipe and of lesser cross-section.

In witness that I claim the foregoing I have hereunto subscribed my name this 15th day of March, 1927.

WALTER C. STONE.
